UNITED STATES PATENT OFFICE.

WINTHROP MURRAY CRANE, OF DALTON, MASSACHUSETTS, ASSIGNOR TO
ALBERT G. GOODALL, OF NEW YORK, N. Y.

MANUFACTURE OF ORNAMENTAL PAPER.

SPECIFICATION forming part of Letters Patent No. 293,228, dated February 12, 1884.

Application filed July 5, 1883. (No model.)

To all whom it may concern:

Be it known that I, WINTHROP MURRAY CRANE, a citizen of the United States, residing in Dalton, in the county of Berkshire and State of Massachusetts, have invented a new and useful Improvement in the Manufacture of Ornamental Paper, of which the following is a specification.

My invention relates to a method of printing or coloring paper during the process of manufacture. Prior to my invention the coloring of paper had been effected by dyeing the pulp before forming the same into paper, whereby the body of the sheet was made of a uniform color throughout. Liquid colors were in some cases applied to the unsolidified pulp-web before the same had been pressed or dried, whereby the coloring material was caused to partially penetrate and spread within or through the body of the web in an irregular manner, and the web after compression and drying has also been superficially dyed by completely immersing the same in a colored liquid size. My invention differs essentially from these; and it consists in applying the coloring material to either or both surfaces of the continuous web of paper after the same has been solidified and the greater part of its moisture expelled by passing through the press-rolls of the paper-making machine. It embraces a continuous process of printing of one or more colors upon a portion or upon the whole of either or both surfaces of the paper, or the imprinting thereupon of designs or figures of any kind. My improved process is not only well adapted for producing paper for bank-notes, drafts, checks, certificates, passage-tickets, and similar vouchers, in which it is necessary or desirable to guard against a fraudulent removal of writing from the surface of the paper, or the alteration of figures, letters, or characters upon the same; but it is also applicable to the manufacture of ornamental striped, figured, or colored paper for any purpose for which such paper is commonly employed.

In the accompanying drawings I have shown a portion of a paper-making machine embracing the parts necessary to enable one method of practicing my invention to be understood, in which—

Figure 1 shows in section a portion of such

machine, together with mechanism which may be used for applying the colors to the paper; and Fig. 2 is a front view of the same.

55

In practicing my invention I prefer to make use of an ordinary paper-making machine—such, for example, as the well-known Fourdrinier machine. The pulp is prepared and refined in the usual manner, being afterward diluted with water and formed into a continuous sheet or web upon an endless wire cloth or apron, whence it is transferred to a felt blanket, still in a green and unsolidified condition. This blanket conveys the web to a series of two or more pairs of press-rolls, by which it is consolidated and compressed and the greater part of its moisture expelled. The terminal pair of rolls of the series is shown at A A in Fig. 1 of the drawings, which represents a part of the well-known Fourdrinier machine. In the ordinary process of paper-making the web *w* after emerging from the press-rolls is next conveyed directly by an endless belt to the first of a series of steam-heated hollow drying-cylinders, B C, &c., which revolve slowly by power and serve to gradually dry the paper as it passes along and around them in the direction indicated by the arrows in the figure.

80

The apparatus for printing or coloring the paper according to my invention may be mounted upon the frame F of the Fourdrinier machine at a point between the press-rolls A A and the first drying-cylinder, B. A convenient form of this apparatus is shown in elevation or end view in Fig. 1, and in an enlarged front view in Fig. 2. It consists of a cylinder, G, which may be termed the "color-roller," and which is so mounted that its lower portion is immersed, as it revolves, in a coloring liquid or dye, *d*, contained in a suitable vessel, D. The color-roller G is caused to revolve by means of a pulley, *g*, to which motion may be imparted from a belt connected to any convenient portion of the machinery.

85

A printing-roller, H, is mounted in bearings or journals above the color-roller G, and may receive its motion therefrom by friction. Above the printing-roller is a small jockey-roller, I, which may be caused to press, by means of springs or otherwise, against the printing-roller H. The web of paper *w* in its passage through the machine, as indicated by

100

the arrows, is led between the printing-roller H and the jockey-roller I, and hence when the machine is in operation the coloring-matter is taken by the printing-roller H from the color-
5 roller G as it revolves, and is continuously transferred to or imprinted upon the under-
most surface of the web of paper w. In illustration of this process, I have shown in Fig. 2
10 a simple form of printing-roller adapted to
produce a design consisting of a series of lon-
gitudinal parallel colored stripes upon the web.
It is evident that a great variety of other
15 and different designs may be produced in the
same manner simply by varying the design
upon the surface of the printing-roller H. If
a plain printing-roller is used, without any de-
sign whatever upon its surface, a uniform tint
20 of any required color may be imparted to the
paper. By using variously-grooved rollers,
such as shown in the drawings, any required
number of parallel stripes may be imprinted
upon the paper, and by employing two or
25 more separate rollers, G, upon the same axis
different colors may be applied simultaneous-
ly. Ornamental designs—such as national
flags, handkerchiefs, or the like—may be en-
graved upon the surface of the roller H and
30 transferred in one or more colors to the paper
web as it passes through the machine.
In case it is desired to apply color or imprint
designs on both sides of the paper, I make use
35 of a second set of rollers, G', H', and I', so
that the web w, after passing the first drying-
cylinder B, and thus drying the color first ap-
plied, may be led over the roller C, and thence
on through the machine in the usual manner.
40 It is obvious that any special ornamental de-
sign or pattern engraved upon the printing-
roller H will be repeated upon the web at every
revolution of the said roller. A cutting-ma-
chine may be so adjusted in connection with
45 the Fourdrinier machine that sheets will be
automatically cut off from the continuous web

after sizing and drying, so that each separate
sheet will contain one copy of the design im-
printed upon the roller, which design will ap-
pear on one or both sides of the sheet, as the
case may be. 50

By applying the color in the manner hereinbefore described—that is to say, after the web has been pressed and the greater part of its moisture expelled—the color does not penetrate far enough into the fiber of the paper to cause it to spread and become spotted or indistinct; nor can writing be fraudulently erased therefrom without exposing the inner fibers of the paper, and thereby changing its apparent color. By the use of my invention paper may be ornamented in any desired way by the application of designs and colors during the process of manufacture at a trifling cost. 55

I do not desire to restrict my invention to 65
the particular means and appliances which I
have described and shown for practicing the
same.

I claim as my invention—

1. The hereinbefore-described art, method, 70
or process of surface-printing or coloring paper
during the process of manufacture, which con-
sists in applying the coloring material to either
or both surfaces of the continuous web, after
the same has been consolidated and partially 75
dried by passing through the press-rolls of the
machine, as set forth.

2. The new article of manufacture herein-
before described, which consists of a paper sur-
face printed or colored after the web has been 80
compressed and a portion of its moisture ex-
pelled by passing through the press-rolls of
the paper-machine in the process of manufac-
ture.

In testimony whereof I have hereunto sub-
scribed my name this 26th day of June, A. D. 85
1883.

WINTHROP MURRAY CRANE.
